PICKER STICK MOTION TRANSMITTING
DEVICE

John Boyce James, Union, S. C.

Application October 3, 1933, Serial No. 692,003

1 Claim. (Cl. 139—151)

This invention relates to a novel connecting and operating device such as is located between a rockably mounted picker stick and a source of power on a conventional type of loom.

5 Admittedly, I am aware of the fact that many different styles and types of devices have been evolved, used and patented to accomplish this same purpose. It follows, therefore, that the present invention relates specifically to an ap-

10 preciably different and distinctive structural assembly characterized by simplicity and efficiency and calculated to provide a means which accom-

plishes the desired ends and purposes more satis-

factorily.

15 The particular selection and co-ordination of parts utilized in accomplishing the aforesaid aim will become more readily apparent from the following description and drawings.

In the drawings:—

20 Figure 1 is an elevational view of a fragmentary portion of a loom, showing the picker stick, the picker stick power supply mechanism and the improved operating device between the picker stick and said mechanism.

25 Figures 2 and 3 are sectional views on vertical and horizontal planes, taken on the lines 2—2 and 3—3 respectively of Figure 1.

Figure 4 is a fragmentary view showing the ball joint connection between the lever extension attachment and the push-pull rod or link.

30 Referring to Figure 1, I call attention to cer-

tain of the old parts of the machine wherein the machine proper is denoted and differentiated by the letter A. The picker stick is indicated at B, having the usual rocker foot C and adaptor bracket or fixture D. The shaft which supplies motion to the picker stick is distinguished by the reference character E and this is provided with the customary cam F for operating the pivoted

35 swingable depending lever G. All of these are old parts.

The improvement comprises several parts and one of these is designated as an extension unit 5. It comprises a slotted plate 6 having the elongated slot 7 arranged to permit it to be secured by a bolt or the like 8 to the lower end of the swingable lever G. The plate is provided with side retaining and stabilizing flanges 9. Formed integral with this plate is a pendant portion

40 which may be described as a metal strap 10, the same being twisted and connected to the plate, as indicated at 11. The lower end portion of this strap is shaped as indicated at 12 to provide one-half of a ball joint socket. A companion socket plate 13 is bolted at this point, as indicated at 14,

and provided with a correspondingly shaped semi-spherical portion 15. The two semi-spherical portions 12 and 15, when clamped together, form a socket for reception of the ball head 16 formed on one end of the push-pull link or rod 60 17. As shown in Figure 3, the right hand end of this rod is screw threaded, as indicated at 18, and attached by lock nuts 19 and 20 to an adjust-

65 ing coupling 21 which is adjustably bolted, as indicated at 22, between the arms of a U-shaped 65 connecting saddle or yoke 23. This yoke em- braces the intermediate portion of the picker stick B, as indicated in the drawings. This pro- vides a detachable, adjustable connection be- 70 tween the threaded end of the rod 17 and the 70 attaching yoke 23.

This arrangement is believed to be substan-

tially self-accommodating and particularly fitted to serve the purpose of rocking picker sticks back and forth through the reciprocatory universal 75 movement of the tie link or push-pull rod 17. The push-pull rod having ball and joint con-

nection to the lever extension unit 5 permits the power transmission to be automatically regu-

lated to fit varying circumstances. The device 80 provides a positive and dependable drive between the lever G and the picker stick B, whose fea-

tures of accommodation and adaptation appar-

ently transcend those of similar motion trans-

mitting arrangements. A structure of this par-

ticular form appears to be scientifically correct, 85 properly balanced and capable of affording the requisite self-accommodating and equilibrium characteristics necessary to promote progress in this particular line of endeavor. Being especially 90 adapted to fulfill the purposes for which it is intended and quite simple and economical, it is thought that a more technical or theoretical ex-

planation is unnecessary.

95 It is thought that the description, taken in connection with the drawings, will enable a clear understanding of the invention to be had. There-

fore, a more lengthy description is thought un-

necessary.

100 While the preferred embodiment of the inven-

tion has been shown and described, it is to be understood that minor changes coming within the field of invention claimed may be resorted to if desired.

I claim:—

105 A device of the class described comprising a substantially U-shaped strap-like yoke adapted to embrace a picker stick, a frame-like coupling member mounted between the free end portions of the arms of said yoke, bolt and nut means 110

for adjustably connecting said member to said arms, a power conveying link threaded at one end, said threaded end being adjustably and detachably connected with said coupling member, 5 and a slotted plate adjustably and detachably connectable to a power supply lever, said plate

being formed with a depending portion, said portion being provided with a ball joint socket, the adjacent end of said rod having a ball joint connector mounted for universal movement in said socket.
